[57] CLAIM

The ornamental design for a truck cab for trucks, as shown and described.

DESCRIPTION

FIG. 1 is a left side elevational view of the truck cab for trucks embodying our novel design, the right side being a mirror image thereof;

FIG. 2 is a perspective view from the right front thereof;

FIG. 3 is a front elevational view thereof;

FIG. 4 is a rear elevational view thereof; and

FIG. 5 is a top plan view thereof.
